(57) **CLAIM**

The ornamental design for an inhaler-module holder, as shown and described.

DESCRIPTION

FIG. 1 is a perspective view of Applicant's inhaler-module holder;

FIG. 2 is a rear view thereof;

FIG. 3 is a side view thereof;

FIG. 4 is a top view thereof; and,

FIG. 5 is a bottom view thereof.

The broken line showing of the inhaler in FIG. 1 is included for the purpose of illustrating environmental structure and forms no part of the claimed design.
